US0D1080747S

(12) **United States Design Patent** (10) **Patent No.:** **US D1,080,747 S**
(45) **Date of Patent:** **** Jun. 24, 2025**

(54) **LID**

(71) Applicant: **YETI Coolers, LLC**, Austin, TX (US)

(72) Inventors: **Dustin R. Bullock**, Austin, TX (US);
Hector Barea, Austin, TX (US); **Rafael Moreno**, The Woodlands, TX (US)

(73) Assignee: **YETI Coolers, LLC**, Austin, TX (US)

(**) Term: **15 Years**

(21) Appl. No.: **29/863,277**

(22) Filed: **Dec. 16, 2022**

(51) **LOC (15) Cl.** **07-02**

(52) **U.S. Cl.**

USPC **D7/392.1**

(58) **Field of Classification Search**

USPC D7/392.1, 392, 387, 391, 396.1, 396.2,
D7/397; D9/434–436, 440, 446, 447, 449
CPC A45F 3/18; B65D 2251/0003; B65D
2251/08; B65D 47/0885; B65D 47/0876;
A47G 19/2272

See application file for complete search history.

(57) **CLAIM**

The ornamental design for a lid as shown and described.

DESCRIPTION

FIG. 1 is a top, front, left perspective view of a lid showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front, left perspective view of our new design in its exemplary environment.

The broken lines are shown for the purpose of illustrating both parts of the article as well as environmental subject matter of an exemplary container. None of the broken lines form part of the claimed design.

1 Claim, 8 Drawing Sheets

US D1,080,747 S
